US0D1096327S

(12) **United States Design Patent** (10) **Patent No.:** **US D1,096,327 S**
(45) **Date of Patent:** **** Oct. 7, 2025**

(54) **FREEZER**

(71) Applicant: **Shenzhen Maining Innovation Technology Co., Ltd.**, Shenzhen (CN)

(72) Inventor: **Huifeng Huang**, Shenzhen (CN)

(73) Assignee: **Shenzhen Maining Innovation Technology Co., Ltd.**, Shenzhen (CN)

(**) Term: **15 Years**

(21) Appl. No.: **29/950,026**

(22) Filed: **Jun. 28, 2024**

(30) **Foreign Application Priority Data**

Jan. 12, 2024 (CN) 202430022143.7

(51) **LOC (15) Cl.** **07-10**

(52) **U.S. Cl.**

(57) **CLAIM**

The ornamental design for a freezer, as shown and described.

DESCRIPTION

FIG. 1 is a front, left and top perspective view of a freezer showing my new design;

FIG. 2 is rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

(Continued)

FIG. 8 is a bottom plan view thereof.

The broken lines depict portions of the freezer that form no part of the claimed design.

1 Claim, 8 Drawing Sheets
